UNITED STATES PATENT OFFICE.

FRANK W. JUDERJAHN, OF MILWAUKEE, WISCONSIN, ASSIGNOR OF ONE-HALF TO
JOHN LUBENOW, OF MILWAUKEE, WISCONSIN.

HOT-WATER HEATER.

Application filed September 30, 1922. Serial No. 591,516.

To all whom it may concern:

Be it known that I, FRANK W. JUDERJAHN, a citizen of the United States, and resident of Milwaukee, in the county of Milwaukee and State of Wisconsin, have invented certain new and useful Improvements in Hot-Water Heaters; and I do hereby declare that the following is a full, clear, and exact description thereof.

10 This invention relates to hot water heaters, and is particularly directed to a heater adapted to use illuminating gas.

In the use of hot water heaters, which employ ordinary illuminating gas for the fuel, two general practices have been followed, namely:—that of connecting the discharge vent for the products of combustion directly with a flue, or chimney, and that of allowing the products of combustion to discharge directly into the room in which the heater is mounted. Both of these practices have been found objectionable, for, on the one hand, when the heater is directly connected with the flue, a too rapid circulation of air is produced thru the heater, and a large percent of the heat passes up the chimney; and on the other hand, when the products of combustion are discharged directly into the room, staining of the walls results and objectionable odors are produced. This last mentioned effect is due, primarily, to an incomplete combustion caused by an inadequate circulation of air thru the combustion chamber of the heater.

35 It is to overcome these defects that the present invention is designed, and such invention, therefore, has for its objects, the provision of a heater in which maximum transfer of heat is effected, in which too rapid circulation of air thru the combustion chamber is prevented, and in which the discharge of objectionable fumes into the room and the staining of the walls is avoided.

An embodiment of the invention is shown 45 in the accompanying drawings, in which, the single figure is an elevation of a heater partly in section.

The heater may comprise a combustion chamber 1 which is usually provided with a 50 hinged door, not shown, and which is provided with a burner 2 positioned in the lower end of the combustion chamber, or casing. The heating coil 3 usually comprises a copper tube in the form of a helix, 55 and equipped with inlet and outlet fittings

4 and 5. The upper portion of the combustion chamber is contracted, as indicated at 6, and is provided with an upturned flange 7 and a central upper outlet 8. A relatively short length of pipe 9 is fitted around the 60 flange 7, and provides a stack of relatively limited extent for the heater. The upper end of this pipe supports a conical cap 10, which is held in spaced relation to said upper end by means of angularly formed 65 brackets 11. It will be seen, from the invention thus far described, that the necessary draft, or suction, for insuring an adequate circulation of air for complete combustion is provided by the pipe 9, and that the flow 70 of heated products of combustion thru the heater is controlled by means of the conical cap 10.

It has been found that choking may occur 75 between the cap 10 and the pipe 9, and that such choking may be entirely prevented by the provision of a series of apertures 12 in the upper end of the pipe 9.

It is also apparent that extreme difficulty 80 would be encountered in effectively positioning the conical cap 10 with reference to the pipe 9, to secure the exact rate of flow of the products of combustion which corresponds to the ideal combustion. However, the desired rate of flow may be accurately 85 secured by providing apertures 12 in the upper end of the pipe 9, their number and size being so chosen that the exact area of outlet for the pipe 9 is secured.

It will further be seen that choking, or 90 banking of the discharged products of combustion beneath the eves, or edges, of the conical cap cannot occur, for the discharged products of combustion are blown sidewise from beneath the conical cap by the outwardly flowing streams from the openings 12.

It will further be seen that the downwardly directed products of combustion 100 from the cone, or baffle member, 10 are directed outwardly by the outwardly passing streams from the pipe 12, so that intimate mixing of the outside air with the products of combustion is secured, and such products of combustion are therefore cooled by the entrained air. This prevents the formation of objectionable odors, and also prevents the products of combustion from striking the walls of the room in an unbroken, or unmixed, stream. It has been found that com- 105 110

plete combustion is secured by this invention, and that the walls of the room, in which the heater is positioned, are not stained.

5 From actual experiments conducted with a heater constructed in accordance with this invention, it has been found that the time required for heating a given volume of water to a given temperature is approximately 10 only two-thirds as great as that required for heating the same volume of water to the same temperature when the heater was connected directly with the flue, or chimney. It is, therefore, apparent that the efficiency 15 of hot water heaters has been very greatly increased by this invention, and that a more perfect combustion of gas is secured.

I claim:

20 A hot water heater having an open bottom and provided with a burner therein and having a top provided with a discharge opening, a pipe secured to said heater and

forming a continuation of said discharge opening, a conical cap mounted above said pipe in spaced relation thereto and extending outwardly and overhanging the upper edge of said pipe and providing with said pipe a constricted passage way outwardly and downwardly for the products of combustion to thereby retard the flow of the 25 products of combustion, said pipe having a plurality of horizontal rows of apertures immediately adjacent said conical cap, the upper of said rows aligning with the bottom edge of said cap, said apertures adapted to 30 permit the products of combustion to pass radially outwardly and to mingle with the downwardly and outwardly flowing products of combustion from beneath the cap.

35 In testimony that I claim the foregoing 40 I have hereunto set my hand at Milwaukee, in the county of Milwaukee and State of Wisconsin.

FRANK W. JUDERJAHN.
